UNITED STATES PATENT OFFICE.

HERMAN A. HACKELING, OF NEW YORK, N. Y.

STATION-INDICATOR.

SPECIFICATION forming part of Letters Patent No. 625,553, dated May 23, 1899.

Application filed August 9, 1898. Serial No. 688,145. (No model.)

To all whom it may concern:

Be it known that I, HERMAN A. HACKELING, a citizen of the United States, residing at New York, in the borough of Manhattan and State 5 of New York, have invented certain new and useful Improvements in Station-Indicators, of which the following is a specification.

This invention relates mainly to station-indicators of that class which are attached to 10 passenger-cars and in which as the car passes the station or street the indicating mechanism is operated so as to indicate the next station or street to the passengers.

The object of the invention is to provide an 15 improved form of actuating mechanism for the indicator, so that the indicating mechanism may be used when the cars are moved in either direction.

Further objects are to generally simplify 20 and render efficient the street-indicating mechanism of this class.

The invention consists of certain features 25 of construction and combinations of parts to be hereinafter described and then particu- larly claimed.

In the accompanying drawings, Figure 1 is a vertical longitudinal section of a portion of a car with my improvements applied thereto. Fig. 2 is a face view of the indicating mech- 30 anism. Fig. 3 is a vertical longitudinal sec- tion of the same on line 3 3, Fig. 4; and Fig. 4 is a vertical section on line 4 4, Fig. 3. Fig. 5 is an enlarged detail view, partly in section, 35 of the actuating mechanism for the indicator, showing the same in one position; and Fig. 6 is an elevation of the same, showing the parts in another position just after the indicator has been shifted. Fig. 5^a is a side elevation 40 of the notched disk shown in connection with the detents. Fig. 5^b is a detail in vertical section through the upper end of the reciprocating rod, showing how the check-pawl is mounted thereon. Fig. 7 is a detail elevation of the 45 same parts, showing the double or U-shaped pawl shifted for the return trip of the car. Figs. 8 and 9 are sectional detail views of the mechanism arranged under the bottom of the car. Fig. 10 is a transverse section through 50 one of the rails, showing the raised cam portion. Fig. 11 is a longitudinal sectional view of a portion of a car, showing a modified form of the invention. Fig. 12 is a vertical trans-

verse section through the casing containing the indicating mechanism and showing the modified form of actuating mechanism. Figs. 55 13, 14, and 15 are views of the modified form of actuating mechanism in different positions, corresponding with the positions shown in Figs. 5, 6, and 7, respectively. Figs. 16 and 17 are enlarged detail views, respec- 60 tively, of the actuating-pawl of the modified form and a cross-section on the line 17 17, Fig. 15.

Similar letters of reference indicate corre- 65 sponding parts.

Referring to the drawings, A indicates a car, whether it be an electric, horse, or other car or coach, which is provided with my im- 70 provements for indicating the streets or sta- tions. In the well-known manner the track 75 is provided at the points corresponding with the stations or streets with raised cam por- tions B, which act on the push-pieces B', that are guided in sleeves C, suitably fastened or bolted to the bottom of the car-body. The 80 push-piece B' is held in normally-lowered po- sition by means of a spring b, coiled within the guide-sleeve C, while the other end of the push-piece B' is pivotally connected with the rock-arm d at the inner end of the rock-shaft 85 D, which is journaled in suitable boxes D', fastened to the bottom of the car-body. The outer end of the said rock-shaft is also pro- 90 vided with a rock-arm d', to which is con- nected the pull-chain e for the indicating 95 mechanism that is contained in the car-body. There is nothing new in this particular mech- anism arranged on the body of the car, and my invention resides in the actuating mech- anism arranged in the car.

In Figs. 2 to 7 my improvements are clearly 100 illustrated. Fixed in one end of the interior of the car A is a case or cabinet E, and in a suitable bearing-frame E', arranged in the said case, is journaled a pair of drums F F', and upon these drums is wound the indicating band or apron I, which is guided over suitable guide-rods I', fixed to the frame E'. The indicating band or apron I is provided either on one or on both sides at proper in- 105 tervals with the names of stations or streets in the well-known manner, so that the indicator will show the names of the stations or streets whether the cars move in one or another di-

rection. In case the car returns by the same route it had taken previously the indicator will show the stations or streets on the returning route in the reverse succession, as the band is simply unwound from the drum onto which it is wound and again wound up during the next trip. In this case it is evident only one side of the band needs to bear the names of stations or streets. In those cases, however, where the cars return by a route different from the one taken before the band or apron is provided with the names of the stations or streets on both sides, one side being necessary for each route. To effectuate in this event the correct indication of stations or streets, the front or face plate of the case E is provided with upper and lower observation slots or openings e^1 e^2 , respectively, and corresponding with the two drums F F', bearing the band or apron, which shows a different side on each drum. According to the route by which the car may be moving, the one or the other slot is closed by means of any suitable arrangement, as by doors D^0 D^X , hinged to the front plate of the case, as shown in Figs. 2 and 3. That only one observation-opening is necessary when the car returns by the same route it had taken previously is evident. The chain e , previously referred to, passes through the bottom of the car and is guided at its upper end around a suitable pulley e^3 and through an opening in the case E, in which the said upper end of the chain is attached to the lower end of a reciprocating and weighed rod G, that is guided in a suitable guide g' , fixed to the inner wall of the case. To the upper end of the rod G is pivoted at h an oscillatory and U-shaped or double actuating-pawl H, this pawl being adapted to be shifted to one side or the other and held in shifted position by means of a suitable spring. J J' are bent plate-springs which diverge or flare outwardly from a pivot j , which is journaled in the car, so that it can be rocked by a suitable knob or button J^2 . (See Fig. 4.) The free ends of the springs J J' span the double pawl, so that each can engage with the corresponding end of said pawl. Only one spring at a time, however, can bear against the double pawl. The recessed ends h' of the double or U-shaped pawl H are adapted to take against laterally-projecting pins k , that are arranged in circular series on one side of a rotary disk K, that is fixed on the extended end of the shaft F^2 of the lower drum F'. By the engagement of the pawl H with the lateral pins k on the disk K the latter is rotated, and through the medium of a gear-wheel L, which is fixed on the shaft F^2 and that intermeshes with another gear-wheel L', fixed on the shaft of the drum F, both of said drums are simultaneously turned in opposite directions. The disk K is provided at suitable intervals on opposite sides of its periphery, corresponding with the distance apart of the pins k , with notches or recesses k' k^2 , respectively, into which the

points or beveled noses m of detents M M' are adapted to take. The notches k' at one side of the periphery of the disk K are beveled in opposite direction from the notches k^2 at the opposite side, while the noses m , which take in said notches, are beveled correspondingly thereto. The detents M M' diverge from pivot j , on which the springs J J' are fixed. Hung on the same pivot h with the double pawl H is a check-pawl S, which is made quite broad at its pivoted end and tapering to a point at its free end. It is mounted so as to extend in an upward direction between the ends of the double pawl and so that it can be shifted or tilted from side to side. The movement of the check-pawl is limited by a pin h^0 , passing through the rod G above the pivot h and through a curved slot in the said check-pawl. (See dotted lines, Figs. 5 and 7, and detail view, Fig. 5^b.) The operation of this form of the invention is as follows: As the car passes a station or street the push-piece B' is raised by the cam B on the track-rail, the shaft D is rocked, and a downward pull exerted on the pull-chain e , which thereby raises the reciprocating rod G. It is assumed that the U-shaped or double pawl H has been swung over into the position shown in Fig. 5 by turning the knob J^2 on pivot j in the direction indicated by the arrow, so that the spring J bears upon the corresponding end of the double pawl and the detent M engages by its beveled nose in one of the notches k' of rotary disk. In this position the said end of the double pawl will take against the pins k on that side of the rotary disk K corresponding thereto. When the rod G is being raised, the said end of the double pawl which is in engagement with one of the pins k will impart a partial rotation to the disk K in the direction of the arrow, the distance moved corresponding to that between any two adjacent pins or notches k' and the pawl overcoming the detaining action of the detent M, which prevents the reverse turning of the said disk when not positively turned. The check-pawl pawl S moves up against the lower pin k and prevents the overrotation of the disk. The partial rotation, as described, of the disk K imparts a partial rotation to the drums F F' and shifts the indicating-band I so that the name of the proper street or station is shown through the opening e^2 , the other opening being closed up. The position of the rod G and the pawl H when raised is shown in Fig. 6. Referring to Fig. 7, it will be seen that the U-shaped pawl H has been oscillated by the knob-controlled spring J' so that the other end of the pawl will engage the pin k at the opposite side of the disk K and so that the other detent M' will engage the other series of notches k^2 . The pawl is set into this position just before the return trip of the car, so that whenever the station or street is being passed the disk will be turned in the direction of the arrow and the indicating-band thereby moved in the opposite direction. Be-

fore making the return trip (only, however, when the car takes another route) the opening e^2 is uncovered and the opening e' of the case E covered, so that the stations or streets 5 on the opposite side of the indicating band or apron will be disclosed. By thus constructing the actuating mechanism it will be observed that the same can be quickly adjusted so that the stations or streets, whether the car 10 run in one or the other direction, may be accurately indicated.

In the modified form of the invention shown in Figs. 11 to 17, inclusive, the rod G has the 15 push-piece B' at its lower end, the intermediate connections before referred to being dispensed with. The rod G is moved normally downward by means of spring g^2 , while the upper end of the rod G is provided with a transversely-slotted head g^3 , in which engages 20 a pin g^4 on the double push-pawl device N. The double push-pawl device N is composed of a cross-bar n' , from which the pin g^4 extends, and two upright arms n^2 . Pawls O O', respectively, are pivoted to the upper ends of 25 the arms n^2 and are directed inwardly by means of springs p , which are fixed at p' to the arms n^2 of the push-pawl device and which act by their free ends upon pins p^2 on said pawls O O'. The pawls O O' are prevented 30 from moving farther in than to a position at right angles to the arms n^2 by means of stop-lugs O², which engage the upper ends of said arms. By this construction the pawls O O' are permitted to perform active service when 35 moving up in contact with the pins k on the rotary disk K; but when the rod G is lowered by its spring g^2 the pawls will slip by and pass the said pins. In this form of the invention the disk K is detained by a single detent Q, 40 which engages the V-shaped notches k⁴. Fixed to the pin g^4 of the pawl device N is a knob or button H⁵, which extends through the case E. This button is moved to one side or the other, so as to shift the push-pawl N to one side 45 or other, according to the direction in which the car may be moving; but otherwise the action of the same is substantially like the main form of the invention, inasmuch as the pawl O will act when going in one direction and the pawl O' when going in the other direction.

It is evident that my mechanism for indicating stations or streets may also be used to locate public buildings or private business places, &c., by substituting for the band or 55 apron bearing the names of stations or streets a band bearing the names of such localities. (See A B C at upper part of Fig. 1.)

Having thus described my invention, I

claim as new and desire to secure by Letters Patent—

1. In a station-indicator for cars, the combination, with the indicating mechanism, provided with an intermittently-rotatable disk having a circular series of pins, projecting therefrom, said disk also having a series of 65 peripheral notches corresponding in number with the pins, of an actuating mechanism, consisting of a reciprocating rod suitably actuated from the track, a shiftable, double-pawl device adapted to engage the said pins 70 at one or the other side of the disk, and a detent adapted to take into said notches, substantially as set forth.

2. In a station-indicator for cars, the combination, with the indicating mechanism, provided with a rotatable disk having a circular series of projecting pins, said disk also having a series of peripheral notches corresponding in number with the pins, of a reciprocating rod suitably actuated from the track, a 80 U-shaped pawl pivoted to said rod, said pawl being adapted to be shifted to one or the other side for engagement with the pins at one or the other side of the disk, a pair of pivoted and diverging detents adapted to take into said 85 notches, and a pair of springs also diverging from the pivot of said detents and bearing on the ends of said pawl, substantially as set forth.

3. In a station-indicator for cars, the combination, with the indicating mechanism, provided with an intermittently-rotatable disk, of a reciprocating rod adapted to be actuated from the track, a shiftable double-pawl device constructed to suitably engage the disk at one or the other side, and a check-pawl pivoted at the upper end of said rod and co-operating with the said disk so as to prevent over-rotation thereof, substantially as set forth.

4. In a station-indicator for cars, the combination with the case provided with two observation-openings, arranged one above the other, and suitable means for closing the one or the other of said openings, of two drums, arranged one behind each opening, and an indicating band or apron wound on said drums so that 105 on each drum the opposite surfaces of said band or apron are faced outwardly, said band or apron being provided with a series of names on both surfaces, substantially as set forth.

In testimony that I claim the foregoing as my invention I have signed my name in presence of two subscribing witnesses.

HERMAN A. HACKELING.
